J. ALLAIN

PADLOCK

Filed June 14, 1923

Inventor:
Jacques Allain

By William Clinton

Attorney

UNITED STATES PATENT OFFICE.

JACQUES ALLAIN, OF MONTREAL, QUEBEC, CANADA.

PADLOCK.

Application filed June 14, 1923. Serial No. 645,425.

To all whom it may concern:

Be it known that I, JACQUES ALLAIN, a subject of the King of Great Britain, residing at Montreal, Province of Quebec, Canada, have invented certain new and useful Improvements in Padlocks; and I do hereby declare that the following is a full, clear, and exact description of the invention, such as will enable others skilled in the art to 10 which it appertains to make and use the same.

The present invention pertains to a combination lock of the type in which the latch releasing member is locked through the instrumentality of spring pressed pins extending from the body of the lock therein.

The improvement resides in a two part pin, one part being known as the pin and the other part as the follower. The shackle 20 retaining member or bolt is movable by means of a plug rotatably inserted in the body. The pins extend from the body into the plug and are in alignment with spring pressed followers within the body. The key 25 which is insertable within the plug has notches formed therein in such a manner as to leave clear the plane of division between the plug and the body. In other words, the contacting ends of the pins and 30 followers are disposed in this plane when the proper key is inserted into the plug, whereby the latter may be rotated to act upon the bolt.

The invention is fully disclosed in the 35 following description and in the accompanying drawings in which:

Figure 1 is an exterior view of a padlock constructed according to the invention.

Figure 2 is a longitudinal sectional view 40 thereof;

Figure 3 is a section on the line 3—3 of Figure 2;

Figure 4 is a view corresponding to Figure 2, showing the shackle in open position; and,

Figure 5 is a section on the line 5—5 of Figure 4.

The device comprises a body 10, at one corner of which is pivoted a shackle 11 50 which is acted upon by a spring 12 tending to force the free end of the shackle out of the body. This member has a notch 13 formed in its inner end and engageable by a spring pressed sliding bolt 14 having a 55 recess 15 in its lower side. A rotatable

plug 16, slotted longitudinally at 17 for the reception of a key, is formed with a lug 18 at its inner end for engagement in the groove 15.

Within the body is mounted a plurality 60 of slideable followers 19 adapted to move into the apertures 20 formed in the plug and extending into the slot 17. These followers are influenced by springs 21 tending to urge them inwardly. In advance of these followers are disposed separate pins 22 which may be of unequal lengths. These pins are received in the apertures 20 and are in alignment with the followers 19 when the lock is not open and the key is not in the slot. 70 Additional spring pressed followers 23 may be provided in the body with balls 22' corresponding to the pins 22.

As shown in Figure 2, the key must be 75 of such construction that when inserted into the plug, it will displace the pins in such a manner that the ends thereof which contact with the followers will form a straight line in the plane of division between the plug and the body. At the same time the 80 followers 23 are moved away from the plug which can now be rotated by the turning of the key. As the plug is turned, the lug 18 moves the bolt 14 out of the notch 13, and the shackle 11 springs open, as illustrated in Figure 4.

The various pins and followers may be 85 inserted through the sides of the body, the openings for the pins and springs being subsequently closed by slides 24. A groove 90 25 is formed partially upon the circumference of the plug, and is adapted to receive a pin 26 passing through the body. By means of the pin the extent of rotation of the plug is limited.

While a specific embodiment of the invention has been illustrated and described, it is to be understood that various alterations in the details of construction may be made 95 without departing from the spirit of the 100 invention as indicated by the appended claim.

Having thus fully described the invention, what I claim as new and desire to protect by Letters Patent is:—

A lock comprising a body and a shackle, a bolt adapted to lock the shackle within the body, a movable element within the body adapted to draw said bolt out of engagement with the shackle, said element having 110

a longitudinal key slot, pins slidably mounted in the movable element and adapted to extend into the body and into one edge of the slot, spring pressed followers mounted in the body and adapted to act on said pins, additional spring pressed followers mounted in the body and adapted to extend

to the opposite edge of said slot, and balls mounted in the movable element and engaged by the last named followers.

10

In witness whereof I have hereunto set my hand.

JACQUES ALLAIN.
